UNITED STATES PATENT OFFICE.

WILLIAM L. RUMMEL, OF MCLEAN, NEBRASKA.

BLOCK SYSTEM FOR RAILROADS.

1,101,663.

Patented June 30, 1914.

Application filed December 1, 1910. Serial No. 595,081.

To all whom it may concern:

Be it known that I, WILLIAM L. RUMMEL, a citizen of the United States, residing at McLean, in the county of Pierce and State 5 of Nebraska, have invented certain new and useful Improvements in Block Systems for Railroads, of which the following is a specification.

My invention relates to block systems for 10 railways and particularly to mechanical means, controlled by electricity.

The object of the invention is the more 15 perfect control of trains and the prevention of accidents, and the invention consists in the arrangement and combination of parts and the simplicity and novelty of construction, as will be hereinafter described and pointed out in the claim.

I have illustrated my invention in the accompanying drawing in which—

Figure 1 is a side view of a part of a semaphore mechanism, a part of a track and side rail in the position of open circuit and closed block, the side rail being elevated in connection with which my invention may be used.

Fig. 2 is an enlarged view in side elevation of part of the mechanism for the operation of a semaphore, a part of the casing of the ratchet wheel, a part of the cam wheel and 20 part of the worm wheel casing being broken away, disclosing the worm wheel, rims, ratchet wheel and ratchet. Fig. 3 is a side elevation of Fig. 2. Fig. 4 is a section on the line *x—y* of Fig. 2.

Referring to the illustration, in which like parts are designated by similar figures of reference, 2 is a track rail. A rod 11 provides in practice, for effecting connection with a semaphore-blade (not shown), the lower end of said rod being connected to the shaft 13. This shaft 13 has one end rotatably mounted in the bracket 14 secured to the rail 2 and the other in the cross bar 16 supported by the post and the leg 16^a. This leg 16^a together with the post forms a support for the platform 16^b. An arm 17 is secured to the shaft 13 near the brace 14, the opposite end of the arm being pivoted to a bolt 18 passing freely through the movable rail 19. When the semaphore is released the arm 11 pushes down the bar 12, turning the shaft 13, raising the arm 17 and with it the movable rail. The elevation of the rail is adapted for the operation of a device upon the engine of the train, as shown in a separate application for patent on railway block

system filed by me on April 13, 1909, Serial Number 489727. The rail is similarly supported throughout its length by braces 14^a and arms 17^a.

The bar 20 is secured to the shaft 13 and connected by a cable 21 through a coupling 21^a to the arm 22 of the cam wheel 23, which, operated by the motor, restores the semaphore to normal position after the train passes out of the block, as now described: The cam wheel is free upon the shaft 24 Figs. 2 and 4, adapted to revolve in a supporting frame or casing 33, supported on an upright 25 secured to a brace 25^a on the platform 16^b which is attached to the semaphore post and supported on legs 16^a. The cam wheel has three steps, the normal 26, the first 28 and the second, 27. Secured to the shaft 24 is a ratchet wheel 29 inclosed in a casing 30, which is secured to the cam wheel 23 and has an opening on one edge and is free upon the shaft. The ratchet wheel is engaged by a pawl 31, pivotally secured to the casing 30 and held to engage the wheel by a spring 32, 30 the free end of the pawl adapted to project through the opening in the casing. Secured to the shaft and within the casing 30 is a worm gear 34 operated by a worm 35 which is turned by a motor 36 through a connecting rod 37. Between the casings 30 and 33 and adjustably secured to the casing 33 is a fan-shaped segment 38 having a rim 39 projecting over the casing 30. Within this rim is secured an adjustable rim 40 by means of screw bolts 41 and 42 which pass through the rim 39 and into the rim 40. The adjustable rim is adapted to engage the free end of the pawl as the cam wheel and casing 30 revolve together and to release the pawl from the ratchet wheel as the wheel and casing approach the rim. A moving contact finger 42^a is pivoted to the axis 43 secured to the support 44 on the casing 33, the opposite end of the finger, 45, forming an approximately 45 right angle and the two parts being separated by insulation. The part 45 is provided with a roller 46 which works upon the cam wheel, and the part 42^a is adapted for contact with the points 47^a and 48^a which are secured to the support 44 and protected by insulation, the contact points being connected with a circuit including the semaphore, through wires 49 and 102 and a binding post 49^a. The wire is curled, somewhat in the form of a spring, in order that the slack of the wire may be taken up as the finger moves

back and forth. The same not forming any part of the invention, a further description thereof is not in order herein. A coil spring 59 connects the part 45 with the support 44, releasing the finger and holding it away from the points in normal position when not engaged by the steps of the cam wheel.

When the motor is in operation the action of the worm on the worm gear slowly revolves the shaft 24 which turns with it the ratchet wheel 29, and by means of the pawl, the casing 30 and cam 23, the cam being driven by the casing, and the circuit through the moving finger and contact points is broken, the semaphore having been restored. The arm 22 is in the position shown and the free end of the pawl 31 has just engaged the rim 40, starting to release the ratchet wheel and cam. The action of the semaphore mechanism through the cable 21 pulls the arm 22 down to a vertical position, Fig. 1, so that the pawl is free of the rim and again engages the ratchet wheel. The cam is thus moved so that its first step is brought under the roller 46, moving the finger to the point 47^a and closing a circuit not shown. The action of the worm carries the ratchet wheel around to where the step 27 of the cam engages the roller and moves the finger to contact 48^a, closing a different circuit. As the cam is moved around until the roller drops

off the step 27, the arm 22 and cable 21 raise the bar 20, which turns the shaft 13, raising the rod 11 and restoring the semaphore.

I wish in this application to disclaim for 35 this invention all rights or claims not properly belonging to this invention and already made or hereafter made in the separate application for patent above referred to.

Having described my invention, what I 40 claim as new and desire to secure by Letters Patent, is,—

In a railway, the combination with a pivoted depressible rail adjacent to one of the track rails, a shaft, a cam wheel freely 45 mounted thereupon, a casing loosely mounted upon the shaft and operatively connected with said cam wheel, a ratchet wheel actuated by the shaft, a pawl pivoted upon said casing and engaging said ratchet wheel, a 50 motor geared to said shaft, an arm secured to said cam, and a flexible connection between said arm and depressible rail for raising and lowering said rail.

In testimony whereof I have signed my 55 name to this specification in the presence of two subscribing witnesses.

WILLIAM L. RUMMEI
